[57] **CLAIM**

The ornamental design for the utility rake, as shown and described.

DESCRIPTION

FIG. 1 is a back view in perspective of a utility rake showing my new design;

FIG. 2 is a back elevational view of the utility rake shown FIG. 1;

FIG. 3 is a right elevational view of the utility rake shown in FIG. 1 with the left view being a mirror image;

FIG. 4 is a front view in elevation of the utility rake shown in FIG. 1;

FIG. 5 is a top plan view the utility rake shown in FIG. 1; and,

FIG. 6 is a bottom view of the utility rake shown in FIG. 1. The broken line showing of a fragmented handle is for illustrative purposes only and forms no part of the claimed design.
